DESIGN FOR A TEXTILE FABRIC OR SIMILAR ARTICLE

Emanuel Castro, New York, N. Y., assignor to Yale Fabrics Corp., New York, N. Y.

Application November 17, 1936, Serial No. 65,962

Term of patent 3½ years

To all whom it may concern:

Be it known that I, Emanuel Castro, a citizen of the United States of America, residing at 74 West 38th Street, New York, New York, have invented a new, original, and ornamental Design for a Textile Fabric or Similar Article, of which the following is a specification, reference being had to the accompanying drawing, forming a part thereof.

The figure is a plan view of a textile fabric showing my new design. The dot and dash lines on the drawing show the design unit, which unit is repeated in staggered succession, as indicated by the angles A and A'.

I claim:

The ornamental design for a textile fabric or similar article, as shown and described.

EMANUEL CASTRO.
